U.S. Appl. No. 29/605,567, filed May 26, 2017, Koury et al.

Primary Examiner — Marianne N Pandozzi

(74) Attorney, Agent, or Firm — Wolf, Greenfield & Sacks, P.C.

(57) CLAIM

The ornamental design for a beverage machine, as shown and described.

DESCRIPTION

FIG. 1 is a top, front, right side perspective of the beverage machine according to our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines illustrate portions of the beverage machine that form no part of the claimed design.

1 Claim, 7 Drawing Sheets
